SIGHTING-IN TARGETS

Paul G. Curren, 51½ W. Main St., Shelby, Ohio
 Filed Jan. 27, 1961, Ser. No. 85,424
 12 Claims. (Cl. 273—102)

This invention relates broadly to sighting-in weapons and is more particularly concerned with a target for the sighting-in of rifles or the like on short target ranges for long range firing.

In hunting, and particularly in large game hunting, the rifle sights are often set for a range of 200 yards, or more. The adjustment of the sights commonly referred to as "sighting-in" for such a range is extremely important and must be accomplished with a high degree of accuracy. Heretofore, to get this accuracy it has been necessary to use a target range of the distance to which the rifle is to be sighted in. In many cases it is impossible to find a target range of sufficient length so the sighting-in is done by approximation on shorter ranges, frequently 100 yard target ranges.

By one prior technique a standard target is placed at 100 yards. The rifle is aimed at the bull's-eye and fired. Preferably several rounds are fired to obtain a shot group. With this prior method the location of the group is visually observed. If, in the example distances cited, a group appeared to be grouped about 3 inches above the center of the bull's-eye the rifle has been considered sighted in. This method is quite inaccurate and subject to many errors.

This invention overcomes these and other limitations of the prior art of sighting-in.

This invention utilizes what is known as "trajectory height" which can be accurately determined in conjunction with a target having an aiming bull's-eye spaced a predetermined and preselected distance below the scoring bull's-eye on a conventional target. Trajectory height, as used herein, means the height of the parabolic path of travel of a round above the line of sight at a given point. Broadly speaking, according to this invention a sighting bull's-eye is placed on the line of sight and a scoring bull's-eye on the determined parabolic path of travel.

A principal object of this invention is to provide a target usable on a short target range to sight-in a rifle or the like for long range firing.

A more particular object of this invention is to provide a target according to the above object having a sighting bull's-eye and a scoring bull's-eye in a predetermined vertical spaced relationship.

A more specialized object of this invention is to provide a target for sighting-in rifle having a contrasted sighting bull's-eye vertically spaced from the scoring bull's-eye a predetermined distance.

Other objects and fuller understanding of the invention may be had by referring to the following description and claims taken in conjunction with the accompanying drawings in which:

FIG. 1 is a diagrammatic representation of a rifle being sighted on a short target range for long range sighting-in showing the line of sight and the parabolic trajectory path of a round fired for a given long range distance with a target interposed at the shorter range, with the target being shown rotated 90°, and with both the rifle and the target on a greatly enlarged scale with respect to the range distance.

FIG. 2 shows a target having a scoring bull's-eye and concentric scoring rings and a sighting bull's-eye spaced below the scoring bull's-eye in contrast with its background.

FIG. 2a is an adhesive-backed sighting bull's-eye to be placed on any existing target, selectively securable to any desired trajectory height;

2

FIG. 3 is an alternate embodiment of FIG. 2;

FIG. 3a is an adhesive-backed sighting bull's-eye to be placed on any existing target, selectively securable to any desired trajectory height;

5 FIG. 4 is another alternate embodiment of FIG. 2; and

FIG. 4a is an adhesive-backed sighting bull's-eye to be placed on any existing target, selectively securable to any desired trajectory height.

10 Referring now to the drawings and particularly FIG. 1, the target and method of sighting-in are shown.

The rifle to be sighted in its designated by the reference character 10. The rifle 10 includes a muzzle 11 and a sighting device 12. The angular relationship between the sighting device 12 and the muzzle 11 can be changed. The line of sight of the sighting device is shown by a broken straight line 13. The path of a fired round is designated by the broken line 14. Due to the force of gravity, a round fired from the rifle 10 will not follow a straight line when it leaves the muzzle 11, but will follow the curved path 14 which is substantially parabolic.

This parabolic trajectory path intersects the line of sight at a down range point 15. It will be noted that the lines 13, 14, also intersect near the rifle 10. Because of 25 the distance involved this crossing can be treated as if it occurs at the end of the muzzle 11. The said round travels along the path 14 to a high point 16 which is located about one half the distance from the end of the muzzle 11 to the down range point 15. The height of this 30 path 14 above the line of sight 13 at any point is known as the trajectory height. The trajectory height of the point 16 is known as the "mid-range" trajectory.

The principle involved in sighting-in a rifle is to set the line of sight 13, and the trajectory path 14 such that the 35 down range point of intersection 15 is at a known distance from the rifle 10. Three factors influence the location of this point 15:

- 40 (1) Muzzle velocity of the round;
- (2) Weight of the projectile; and
- (3) The angle of inclination of the muzzle, with the line of sight.

With any given rifle and type of cartridge the first two of these are constant and known or determinable. Hence, if the angle of inclination is set at a predetermined 45 value the trajectory path 14 and the point 15 are located for all of a given type of cartridge fired from a given rifle. If a target is placed a distance from the rifle equal to the distance of the point 15 from the rifle and the line of sight is positioned to intersect the bull's-eye of the target, a round fired of the given type of cartridge will follow the path of travel 14 and strike the bull's-eye. If, however, the target is placed closer to the rifle than the distance equal to the distance of the point 15 from the rifle, the projectile following the trajectory path will 50 strike the target at a point above the line of sight 13.

In order to sight in a rifle for a given distance, one method is to place a target at the distance to which the rifle is to be sighted in, aim the rifle so that the line of sight passes through the bull's-eye and fire one or more rounds. The target is then examined to see the position of the shots and if such position is not correct the angle 60 between the line of sight and the trajectory path is adjusted and the firing done again until the shots are properly placed.

65 FIG. 2 shows a target having a scoring bull's-eye and concentric scoring rings and a sighting bull's-eye spaced below the scoring bull's-eye in contrast with its background.

70 The present invention makes use of the fact that the trajectory path 14 can be determined and its height above the line of sight 13 can thus be ascertained. According to the present invention a target 20 is placed a given

distance from the rifle, but at a range shorter than the sighting-in range. The target will include a conventional scoring bull's-eye 21 and scoring rings 22 and additionally will include a sighting bull's-eye 26. The sighting bull's-eye 26 is so placed in relation to the scoring bull's-eye that when the line of sight 13 passes through the center of the sighting bull's-eye 26 the determined trajectory height at the target range will be located at the center of the scoring bull's-eye 21. Thus, to sight in a rifle for 200 yards a target may be placed at 100 yards. The trajectory height of a given type of ammunition is then determined at 100 yards for a 200 yard sight setting and the center of the sighting bull's-eye 26 is placed exactly that distance below the center of the scoring bull's-eye 21. When the line of sight of the rifle is adjusted so that it passes through the center of the sighting bull's-eye 26 and the angle of the rifle muzzle with the line of sight is correct for 200 yards, the trajectory height of the projectile at 100 yards will pass through the center of the scoring bull's-eye. Thus a round fired from the rifle will pass through the center of the scoring bull's-eye 21.

To sight-in a rifle the selected sighting-in range is determined and the target range is selected. The trajectory height at the target range is then ascertained. The target 20 is placed at the target range distance from the rifle 10 and the center of the sighting bull's-eye 26 is placed a distance below the center of scoring bull's-eye 21 which is equal to the ascertained trajectory height. A rifle is then aimed at the sighting bull's-eye 26 so that the line of sight passes through the sighting bull's-eye 26 and at least one and preferably a group of rounds are fired. The target is then examined to determine the position of the shots with respect to the scoring bull's-eye. If they are not properly placed therein the angle of the muzzle with respect to the line of sight is changed and another group of rounds is fired and the target again examined. The firing, examining of the target, and correcting of the sights is repeated until the shots are properly placed in the scoring bull's-eye 21.

The trajectory heights of various types of ammunition can be obtained, and the following table gives representative mid-point trajectories for various types of commonly used big game ammunition.

Cartridge	Bullet Weight, Grains	Midrange Trajectory in Inches		
		100 Yards	200 Yards	300 Yards
.348	250	0.9	4.4	11.5
.348	200	0.8	3.8	10.0
.300 Weatherly Magnum	220	0.6	2.3	5.7
.300 H. & H. Magnum	220	0.7	3.1	7.7
.300 H. & H. Magnum	180	0.6	2.4	5.7
.30/06	220	0.8	3.7	9.2
.30/06	180	0.7	2.9	7.0
.300 Savage	180	0.9	3.7	9.5
.270 Winchester	150	0.7	3.0	7.8
.270 Winchester	130	0.5	2.1	5.3
.300 Weatherly Magnum	180	0.4	1.7	4.2

Example I

Assume that the cartridge to be used is a .270 Winchester with a 150 grain bullet, and the rifle is to be sighted in for 200 yards zero, and the available target range is 100 yards. The target is placed at the 100 yard range. Reference to the table above indicates that the mid-point trajectory for this round is 3.0 inches. A target is selected or prepared that has the center of the sighting bull's-eye 26, 3.0 inches below the center of the scoring bull's-eye 21. The rifle is sighted at the sighting bull's-eye 26 and several rounds of the selected cartridge are fired. The position of the shot group is observed and necessary sight adjustments made. A rifle so sighted in would deliver a hit in the killing zone of an animal as small as a pronghorn antelope at any distance from

the gun muzzle up to 400 yards even if the range is misjudged.

If the exact trajectory height is not readily available for the desired sighting-in range and the target range combination it can be very closely approximated in most cases by interpolation and extrapolation.

Example II

Assume it is desired to sight in a rifle for 275 yards on a 100 yard range with a .270 Winchester 150 grain round. The mid-point trajectory is not given for 275 yards, nor is 100 yards the mid-point. The mid-point trajectory for 275 yards would be approximately that for 200 yards plus three-fourths of the difference between the 200 yards and the 300 yard mid-point trajectory; i.e. $3.0 + \frac{3}{4} (7.8 - 3.0) = 3.0 + \frac{3}{4} (4.8) = 3.0 + 3.6 = 6.6$ inches

This equals the trajectory height at the mid-point of 275 yards, i.e. 137.5 yards. Therefore, the trajectory height at 100 yards would be approximately equal to:

$$\frac{100}{137.5} \times 6.6 = \frac{660}{137.5} = 4.8 \text{ inches}$$

Thus, for sighting in of the rifle for 275 yards with the target at a range of 100 yards the center of the sighting bull's-eye 26 should be placed 4.8 inches, below the center of the scoring bull's-eye 21. This is diagrammatically represented in FIGURE 1. Other combinations are readily apparent.

Another advantage, not so readily apparent, is the usefulness of this target placement and sighting in, in correcting canting tendencies on the part of the rifleman. Canting is the twisting of the weapon rotatably on the axis of the barrel so that the sights are not on a vertical plane passing through the barrel of the rifle. A 5° cant will show up in this shot grouping as about a 2-inch lateral displacement at 100 yards, and an 8 to 10 inch lateral displacement at 200 yards.

FIGURES 2 through 4a show several embodiments of targets for sighting in rifles according to this invention. The target 20 has a scoring bull's-eye 21 and a plurality of scoring rings 22. The bull's-eye is white, and the two innermost scoring rings 22 are black. The remaining scoring rings are colored white. A sighting disc 25 is provided having a sighting bull's-eye 26 thereon. Preferably the disc is sized to the size of the scoring bull's-eye. This sighting bull's-eye 26 may be printed or formed integral with the remainder of the target, or it may be printed on a separate material with adhesive 50 backing suitable to affix the bull's-eye on the target at a selected position to correspond with the determined trajectory height.

In FIGURES 2 and 2a, the sighting bull's-eye 26 has its upper portion colored white and its lower portion colored black. This is to afford contrast with the scoring rings upon which it is normally superimposed.

FIGURES 3 and 3a show another arrangement of contrasting appearances as do FIGURES 4 and 4a. In FIGURE 4, the appearance of the sighting bull's-eye of the sighting disc 25 contrasts with the appearance of the sighting ring around the sighting bull's-eye, and the appearance of the sighting ring contrasts with the appearance of the adjacent portions of the scoring rings on the scoring target. The contrasting appearances of the sighting disc 25 are contoured to complete the contour of the adjacent scoring rings on the scoring target.

Although the invention has been described in detail, it is believed to comprise essentially a target for sighting in a rifle or the like for a long range using a short range, the target having a scoring bull's-eye and contrasting scoring rings around the scoring bull's-eye, a sighting bull's-eye of substantially the size of the scoring bull's-eye positioned among the scoring portions and having its center located a predetermined mid-range trajectory height from the center of the scoring bull's-eye, and the sighting

bull's-eye having its surface appearances in contrasting relation to the adjacent scoring portions of the target for that predetermined mid-range trajectory height.

What is claimed is:

1. The combination for sighting-in a rifle or other arms for accurate firing of a missile from full-size ammunition over a distance greater than the available range between the rifle and a target sheet, said combination comprising:

(a) the target sheet having:

- (i) a circular bull's-eye scoring portion;
- (ii) a plurality of ring scoring portions concentrically arranged with respect to one another and with respect to said bull's-eye scoring portion;
- (iii) said bull's-eye scoring portion and at least one of said ring scoring portions having contrasting colors;

(b) a sighting disc being removably secured to the target sheet so as to be superimposed over the scoring portions with the center of said sighting disc spaced from the center of said bull's-eye scoring portion a predetermined distance equal to the trajectory height of the missile fired when the missile is at the available range distance of the total distance for which the rifle is being sighted-in;

(c) said sighting disc having a central bull's-eye sighting portion; and,

(d) said bull's-eye sighting portion being colored to contrast with the adjacent scoring portions when the center of said sighting disc is spaced said predetermined distance from the center of said bull's-eye scoring portion.

2. The combination of claim 1, including, in combination:

(e) said sighting disc further having a circle sighting portion surrounding said bull's-eye sighting portion, and said circle sighting portion being colored to contrast with the coloring of said bull's-eye sighting portion.

3. The combination for sighting-in a rifle or other arms for accurate firing of a missile from full-size ammunition over a distance greater than the available range between the rifle and a target sheet, said combination comprising:

(a) the target sheet having:

- (i) a circular bull's-eye scoring portion;
- (ii) a plurality of ring scoring portions concentrically arranged with respect to one another and with respect to said bull's-eye scoring portion;
- (iii) said bull's-eye scoring portion and at least one of said ring scoring portions having contrasting colors;

(b) a sighting disc being removably secured to the target sheet so as to be superimposed over the scoring portions with the center of said sighting disc spaced from the center of said bull's-eye scoring portion a predetermined distance equal to the trajectory height of the missile fired when the missile is at the available range distance of the total distance for which the rifle is being sighted-in;

(c) said sighting disc having:

- (i) a central bull's-eye sighting portion; and,
- (ii) a ring sighting portion surrounding said bull's-eye sighting portion;

(d) the coloring of the sighting portions contrasting with the coloring of the scoring portions; and,

(e) the coloring of said sighting portions being contoured to complete the circular contour of the adjacent scoring ring portions in the contrasting colored relation when the center of the scoring disc is spaced said predetermined distance from the center of said bull's-eye scoring portion.

4. The combination of claim 3 including, in combination:

(f) the coloring of said ring sighting portion contrasting with the coloring of the adjacent ring scoring

75

portions and the coloring of said bull's-eye sighting portion contrasting with the coloring of the ring sighting portion.

5. The combination of claim 3 wherein said contrasting colors are the colors black and white.

6. The combination for sighting-in a rifle or other arms for accurate firing of a missile from full-size ammunition over a distance greater than the available range between the rifle and a target sheet, said combination comprising:

(a) the target sheet having:

- (i) a circular bull's-eye scoring portion;
- (ii) a plurality of ring scoring portions concentrically arranged with respect to one another and with respect to said bull's-eye scoring portion;
- (iii) said bull's-eye scoring portion and at least one of said ring scoring portions having contrasting colors;

(b) a sighting disc being removably secured to the target sheet so as to be superimposed over the scoring portions with the center of said sighting disc spaced from the center of said bull's-eye scoring portion a predetermined distance equal to the trajectory height of the missile fired when the missile is at the available range distance of the total distance for which the rifle is being sighted-in;

(c) said sighting disc having a central bull's-eye sighting portion;

(d) said bull's-eye sighting portion being colored to contrast with the adjacent scoring portions when the center of said sighting disc is spaced said predetermined distance from the center of said bull's-eye scoring portion; and

(e) the coloring of said bull's-eye sighting portion being contoured to complete the contour of adjacent scoring portions in the contrasting color relation.

7. A target for sighting-in a rifle or like arms for the accurate firing of a missile from full-sized ammunition over a distance greater than the available range between the rifle and the target, said target comprising:

(a) a circular bull's-eye scoring portion;

(b) a plurality of ring scoring portions concentrically arranged with respect to one another and with respect to said bull's-eye scoring portions;

(c) the surface of said bull's-eye scoring portion and the surface of at least one of said ring scoring portions having contrasting appearances;

(d) a circular bull's-eye sighting portion of at least nearly the size of said bull's-eye scoring portion being positioned among said scoring portions and having its center located a predetermined distance from the center of said bull's-eye scoring portion, said predetermined distance being equal to the trajectory height of the missile when it is at the available range distance of the total range for which the rifle is being sighted-in; and,

(e) the surface of said bull's-eye sighting portion having an appearance contrasting with adjacent scoring portions when its center is located said predetermined distance from the center of said bull's-eye scoring portion.

8. The combination of claim 7 including, in combination:

(f) the contrasting surface appearance of said bull's-eye sighting portion being contoured to complete the circular contour of said ring scoring portions in the contrasting surface appearance relation.

9. The combination of claim 8 including, in combination:

(g) a ring sighting portion surrounding said bull's-eye sighting portion and the surface of said ring sighting portion having an appearance contrasting with

the surface appearance of said bull's-eye sighting portion.

10. A target for sighting-in a rifle or like arms for the accurate firing of a missile from full-sized ammunition over a distance greater than the available range between the rifle and the target, said target comprising:

- (a) a circular bull's-eye scoring portion;
- (b) a plurality of ring scoring portions concentrically arranged with respect to one another and with respect to said bull's-eye scoring portion;
- (c) the surface of said bull's-eye scoring portion and the surface of at least one of said ring scoring portions having contrasting appearances;
- (d) a circular bull's-eye sighting portion of at least nearly the size of said bull's-eye scoring portion being positioned among said scoring portions and having its center located a predetermined distance from the center of said bull's-eye scoring portion, said predetermined distance being equal to the trajectory height of the missile when it is at the available range distance of the total range for which the rifle is being sighted-in;
- (e) a ring sighting portion surrounding said bull's-eye sighting portion;
- (f) the surface appearance of said ring sighting portion contrasting with the surface appearance of the adjacent ring scoring portions, and the surface appearance of said bull's-eye sighting portion contrasting with the surface appearance of said ring sighting portion; and,
- (g) the surface appearance of said ring sighting por-

tion and said bull's-eye sighting portion being contoured to complete the circular contour of the ring scoring portions in the contrasting surface appearance relation.

11. The combination of claim 7 wherein said bull's-eye sighting portion is adjacent at least two scoring portions of contrasting surface appearance and is provided with said contrasting surface appearances, and the contrasting surface appearances being contoured to complete the circular contour of the adjacent scoring portions in the contrasting surface appearance relation.

12. The combination of claim 10 wherein said sighting portions are adjacent at least two scoring portions of contrasting surface appearances, both said ring and bull's-eye sighting portions being provided with the contrasting surface appearances of the adjacent scoring portions, the surface appearance of the ring sighting portion being contoured to at least partially complete the circular contour of the adjacent scoring ring portions in the contrasting surface appearance relation, and the surface appearance of said bull's-eye sighting portion contrasting with the surface appearance of the ring sighting portion and being contoured to complete the circular contour of the adjacent scoring portions.
